UNITED STATES PATENT OFFICE.

RICHARD ANDREW LANGERMAN, OF LOUISVILLE, KENTUCKY.

SPINNING-TOP.

SPECIFICATION forming part of Letters Patent No. 688,655, dated December 10, 1901.
Application filed April 15, 1901. Serial No. 55,875. (No model.)

To all whom it may concern:

Be it known that I, RICHARD ANDREW LANGERMAN, residing at Louisville, in the county of Jefferson and State of Kentucky, have made certain new and useful Improvements in Spinning-Tops, of which the following is a specification.

It is my object to provide an improvement in the class of conical wooden tops which are adapted to be spun when thrown with due force by the unwinding of a cord or string duly coiled about them and held fast in the hand. To this end I provide the wooden body of the top with a metal cap or cover and secure the latter by a spike which passes axially through the body and is constructed with an enlarged conical head having a flat portion that abuts the truncated end of the top-body.

In the drawings, Figure 1 is a side view of my preferred form of top. Fig. 2 includes a sectional view of the body of the top and a perspective of the cap and the spike adapted for attachment thereto.

Referring to the drawings, *a* indicates the conical wooden body of the top, *b* the concavo-convex cap thereof, and *c* the metal spike, which is adapted for application to the body *a*. The latter has a central axial passage or opening *a'*, in which the stem of the spike *c* is adapted to fit. When thus inserted, the enlarged conical head *c'* of the spike abuts the truncated end *a''* of the top-body *a*, and the stem of the spike projects far enough through the cap *b* when applied to and covering the conical top of said body *a* to permit it to be riveted down on the cap, and thus secure all the parts *a b c* firmly together. The flat portion of the head *c'* of the spike serves as a support and abutting sur-

face for the top-body *a* when in use, and the cap *b* protects and forms an ornamental appendage of the head of the body *a*, which it is designed to entirely cover. It is particularly useful in the game known as "plugging," in which the wooden body is liable to be battered, indented, cracked, or split by striking contact with other tops thrown by the players. The weight of the head *c'* of the spike places the center of gravity of the top comparatively low, and it serves to prevent the body *a* being cracked or split by repeated concussion on hard surfaces.

What I claim is—

The spinning-top herein described comprising a conical truncated wooden body having an axial passage and having its large end or crown curved gradually from side to side, the spike inserted and passing through said axial passage and provided adjacent to its point end with a conical portion whose end forms a shoulder to abut the truncated end of the body and whose sides are sloped to coincide with the sides of the body, and a protective sheet-metal concavo-convex cap conforming closely to and covering the larger end of the body and extending at its outer edge nearly to the outer edge of the wooden body, the spike being secured to the protective cap, all substantially as described whereby the wooden body is clamped securely between the spike-shoulder and the protective cap and is thereby strengthened against splitting and is protected at its butt-end by the cap which extends over the same, substantially as set forth.

RICHARD ANDREW LANGERMAN.
